US0D1058546S

(12) **United States Design Patent** (10) **Patent No.:** **US D1,058,546 S**
(45) **Date of Patent:** **** Jan. 21, 2025**

(54) **COMMUNICATION RELAY DEVICE**

(71) Applicant: **PHC HOLDINGS CORPORATION**,
Tokyo (JP)

(72) Inventors: **Akihiro Mochizuki**, Gunma (JP);
Tadashi Okada, Saitama (JP); **Fumio Yamada**, Gunma (JP)

(73) Assignee: **PHC HOLDINGS CORPORATION**,
Tokyo (JP)

(**) Term: **15 Years**

(21) Appl. No.: **29/896,242**

(22) Filed: **Jun. 30, 2023**

(30) **Foreign Application Priority Data**

Jan. 6, 2023 (JP) ..... 2023-000098 D

(51) **LOC (15) Cl.** **14-03**

(52) **U.S. Cl.**

USPC **D14/149**; D14/240

(57) **CLAIM**

The ornamental design for a communication relay device as shown and described.

DESCRIPTION

FIG. 1 is a front, top, right side perspective view of a communication relay device showing our new design; FIG. 2 is a rear, bottom, right side perspective view thereof; FIG. 3 is a front bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate portions of the communication relay device that form no part of the claimed design.

1 Claim, 7 Drawing Sheets
